UNITED STATES PATENT OFFICE.

RUSSEL A. COWLES, OF NEW YORK, N. Y., ASSIGNOR TO ANSONIA CLOCK CO., OF BROOKLYN, NEW YORK, A CORPORATION OF CONNECTICUT.

DESIGN FOR AN ASH TRAY OR THE LIKE.

Application filed February 28, 1922. Serial No. 945. Term of patent 14 years.

To all whom it may concern:

Be it known that I, RUSSEL A. COWLES, a citizen of the United States, and a resident of the borough of Manhattan, city, county, and State of New York, have invented a certain new and ornamental Design for an Ash Tray or the like, of which the following is a specification, reference being had to the accompanying drawings, forming a part thereof.

In the drawings—

Fig. 1 is a plan view of a tray illustrating my new and original design.

Fig. 2 is a front elevation of the same, and

Fig. 3 is a side elevation of the same.

I claim—

The ornamental design for an ash tray or the like, as shown.

This specification signed and witnessed this 24th day of February, 1922.

RUSSEL A. COWLES.
